UNITED STATES PATENT OFFICE.

WILLIAM S. DOIG, OF BROOKLYN, NEW YORK.

CLEAT-NAILING MACHINE.

SPECIFICATION forming part of Letters Patent No. 600,685, dated March 15, 1898.

Application filed July 16, 1896. Serial No. 599,407. (No model.)

To all whom it may concern:

Be it known that I, WILLIAM S. DOIG, a citizen of the United States, and a resident of Brooklyn, in the county of Kings and State 5 of New York, have invented certain new and useful Improvements in Cleat-Nailing Machines, of which the following is a specification.

My invention relates to machines for securing cleats placed over depressed box-covers by nailing the same with nails driven through the cleats obliquely as to the inner surface of the sides of the box; and the invention consists in the construction and novel arrangement of parts whereby two cleats on opposite sides of the box are simultaneously nailed at one operation.

Figure 1 is a front elevation of my machine for nailing cleats for fastening covers on boxes. Fig. 2 is a side elevation of the same with a portion of the frame broken away. Fig. 3 is an elevation of a portion of the machine. Fig. 4 is a plan view of presser-plate employed. Fig. 5 is a partial section and 15 partial elevation showing the mechanism for driving nails. Fig. 6 is an enlarged view of self-adjusting guide. Fig. 7 is an enlarged view of self-adjusting guide and chucking-plates. Fig. 8 is an enlarged view of one 20 of the links connecting the cross-head and nail-punches. Fig. 9 is a sectional view of box-support or table A⁷ with pivoted platen A⁸ in position. Fig. 10 is a plan view of the same, showing register-pad y on platen A⁸, with 25 stops e e' and handle e', showing the arc of the circle through which the platen is moved. Fig. 11 is an enlarged view in section of the side, top, (or bottom,) and cleat of a box (the manufactured product of this machine) with 30 a nail f shown in the position in which it has been driven by the operating mechanism thereof. Fig. 12 is a perspective view of a box with four cleats of the top (or bottom) nailed in position. Either pair of cleats, as x 35 and x', represent the product of one nailing operation.

A A are the side frames of the machine, firmly bolted on a base or foundation at the bottom and secured in a firm manner by a 40 cross-girth on top, also by a cross-girth carrying the shaft A⁴, and also by the fixed angular guide-form C², which also acts as a cross-girth,

the whole making the main frame of the machine solid and rigid, and the construction having for its purpose the leaving of an open 55 passage through the machine between the top of the box-support or table A⁷ and the lower edge of the self-centering guides D D to permit the box operated upon to be introduced at the front of the machine and, after being 60 nailed, to be delivered through the rear, thus greatly increasing the working capacity of the machine.

A' is the driving-shaft, upon which is mounted a pinion b³, engaging with a gear A², which 65 also forms a crank o⁵. Loosely mounted on the shaft A' is a pulley A⁵, having a clutch mechanism A⁶ for engaging the shaft. These parts are well known and are fully described in my Patent No. 461,013, dated October 13, 70 1891.

The gear A² engages a gear A⁸, of the same diameter, on shaft A⁴, having suitable bearings in the frame of the machine. On shaft A⁴ is fastened the cam a, which works on a 75 roller a', connected with the box-supporting table A⁷. It will be readily seen that by each revolution of the gear A² the cam a will be revolved and impart a reciprocating motion to the table A⁷. By the substitution of different cams the motion of the table A⁷ can be varied to suit any depth of box to be operated upon. The cam a is not only designed to impart a reciprocating motion to the table, but when the table is elevated thereby the cam 80 85 during the remainder of its revolution forms a rigid support for the table, retaining it rigidly in position.

B is a vertically-reciprocating cross-head guided in the side frames A A and projecting through them. Motion is imparted thereto from the driving-shaft A' through the medium of the connecting-rods a², extended downward to carrier B', guided in the side frames in the same manner as cross-head B, 95 having a rectangular yoke a³, in which slides a block a⁴, having connection with the crank-pin a⁵ on gear A².

On either side of the reciprocating cross-head are pivoted a number of pairs of links 100 C³. (Shown in Figs. 2, 3, and 5.) In this case I use three pairs of links, but can use any number required. The links C³ are pivoted loosely on the cross-head and are carried

up and down thereby. The lower ends of each pair of said links C^3 are pivoted to the corresponding pair of nail-punches c^2 . Each pair of links is deflected outward and downward from the perpendicular on opposite sides through the plane of reciprocation of cross-head B. The angle at which the links C^3 , and through them the nail-punches c^2 , are deflected is determined by the angular guide-form C^2 , in which the nail-punches work. This position of the parts enables one to center the box-support directly beneath the cross-head, and thus to bring the cleats to be nailed parallel with the cross-head.

15 The angular guide-form C^2 is rigidly fixed to and forms part of the main frame of the machine.

Rigidly attached to the angular guide-form C^2 and extending in a right line therewith is 20 a bar C C for holding the nail-boxes c c, which nail-boxes conform to the same angle and are in a right line with the nail-punches. Otherwise the construction of the nail-boxes is the same as described in my patent above referred to.

25 B^{11} is a presser-plate for engaging the top of a box to be operated upon and holding it and the cleats in position during the nailing operation.

30 The presser-plate B^{11} is a flat plate of steel beveled to fit against the inner face of the cleats and corresponding to the outline of the cover of the box operated upon and fitted with recesses for the passage of nails, preferably suspended loosely from the cross-head by four round guide-rods b through four guides b' on the cross-head, in which they fit loosely, and on the upper end of each rod a nut may be used to regulate the depth at 35 which the presser-plate shall hang suspended. Between the presser-plate B^{11} and the guides b' on each guide-rod b a spiral spring b² is arranged and regulated by a collar attached to the rod b. The under edges of the presser-plate are beveled on the four under sides to an angle corresponding with the exposed surface of the cleat. The presser-plate is recessed at intervals, as shown in a plan view in Fig. 4, to permit the passage of the nails.

40 A^7 is a table movable vertically between the uprights A A by means of the cam a, acting on the roller a', journaled in a hanger secured to the under side of the table A^7 .

45 A^8 is a rotary platen pivoted in the center of the table on the pin p and having thereon a registering-pad y, adapted to center the box on the platen. Said platen is provided with a handle e' and stops e e, limiting the rotary motion of the platen to one-quarter revolution, as shown in Fig. 10.

50 D D are self-adjusting guides. (Shown in Figs. 2 and 3 in position in the machine and in Figs. 6 and 7 in detail.)

55 The guides D D may be fixed in any desired position by means of set-screws d and are mounted on brackets D so as to slide inward or outward. Springs b² around the set-

screws d allow the guide-plates to adjust themselves with equal pressure on both sides of the box to be operated upon. The guide-plates are inclined downward and outward on their inner faces, so as to allow the box to enter and to bring it into such position that the cleats to be nailed will be in proper alignment with their corresponding nail-punches. 70 The inner faces, which come in contact with the surfaces of the box, can be faced with hardened steel and will then operate to clinch any nails which may project through the sides of the box. 75

80 Such being the construction of the different parts of my invention, I will now proceed to explain the operation of my machine.

In this machine in practice the nails are driven downward and outward through the 85 cleat at right angles to the exposed surfaces thereof and obliquely into the sides of the box, thereby holding the cover in position. The cover is depressed within the sides of the box to the depth of the cleat, leaving the upper edge of the cleat flush with the top of the side piece against which it rests. Such boxes are used commercially for packing plug-tobacco.

90 In operation a box with a cover and cleats 95 in place is mounted on the pivoted platen A⁸ (shown in Figs. 1 and 2) on the box-support A⁷, and the driving mechanism is started by clutch A⁶ in the usual manner. The cam a elevates the box-support or table and platen, 100 with the box thereon, until it engages the box between the self-adjusting guide-plates D D, which, acting thereon, clamp the sides on the exterior, so as to resist the pressure of the nails when driven, bringing the box into position and alining the cleats. The guides D D also form the anvil by which the nails are clenched. The upward movement of the box against the presser-plate B^{11} depresses the cover vertically to its proper position and the 110 beveled under edges of the presser cause it to exert a pressure obliquely on the cleats, forcing them outwardly and against the interior surface of the sides of the box, holding them firmly in place. This pressure is required to 115 prevent the cleats from splitting during the nailing operation, the tendency to which is a practical difficulty which it has been found essential to obviate. As the table and platen start upward the cross-head starts downward, 120 but moves at a lower rate of speed, the ratio of speed between these parts being fixed and determined according to the depth of the box to be operated upon and is controlled by the shape of the cam. The nail-feeding 125 mechanism is so adjusted that the nails are delivered in the nail-pockets ready for driving during the movement above described. The cam a, continuing its revolution, first 130 brings the box into position and then furnishes a rigid support for the table and plates carrying the box and in conjunction with the guides D D and the presser-plate B^{11} holds it in position during the nailing operation as

within a vise. The cross-head B completes its descent and causes the links C³ to force the punches c² obliquely downward and outward, traveling through their respective guides on the angular guide-form C². This movement of the punches brings them in contact with the respective nails in the corresponding nail-pockets. The nails are thus driven through the front and rear cleats and corresponding sides of the box. The cross-head then returns to its starting position, while at the same time the table returns to its starting position, thus completing the simultaneous nailing operation of two opposite cleats. The two remaining cleats are brought into position for nailing as follows: The platen is moved by means of the handle e' until the handle comes into contact with the stop e in the position e² shown in Fig. 10. The remaining cleats are then nailed, as above described, and on the descent of the table to its normal position the completed box is passed through the rear of the machine while a new box is being placed on the platen.

25 The machine, it will be seen, is operated through two trains of mechanism, the one operated by the reciprocating cross-head B and the other by the cam a.

Having thus described my invention, what I claim, and desire to secure by Letters Patent, is—

30 1. In a nailing-machine for nailing cleats into boxes, in combination, a support for the box, two sets of nail-punches and a vertically-reciprocating cross-head for actuating them, arranged centrally over the box-support, parallel with the cleats to be nailed, and carrying links arranged in diverging pairs and means for connecting the links with the nail-punches and a presser-plate for retaining the cleats in position to be nailed, substantially as described.

35 2. In a machine for nailing cleats into boxes, a support for the box, a vertically-reciprocating cross-head, arranged centrally over the box-support, in combination with duplicate sets of nail-boxes, arranged opposite each other, parallel to the cross-head and obliquely to the ends of the box, nail-punches 40 corresponding to such nail-boxes and connected to the cross-head by links arranged in diverging pairs, substantially as described.

45 3. In a nailing-machine for nailing cleats into boxes, in combination, a nail-punch actuating a vertically-reciprocating cross-head, arranged centrally over and parallel with the cleats to be nailed, and a vertically-reciprocating box-support, carrying a rotary platen, substantially as described.

50 4. In a cleat-nailing machine mechanism for nailing the cleats into boxes, in combina-

tion, means for holding the cleats in position for nailing, a vertically-reciprocating table carrying a rotary platen, and a registering-pad mounted on such platen for the purposes 65 specified.

5. In a cleat-nailing machine, in combination, mechanism for nailing the cleats into boxes, self-adjusting guides for bringing the cleats into adjustment with the nail-punches, 70 means for retaining the cleats when nailed, and a vertically-reciprocating table, carrying a pivoted platen permitting the guides to control the position of the box, substantially as described. 75

6. In a machine for nailing cleats into boxes, in combination, a box-support, nail feeding and driving mechanism, and a yielding plate with beveled edges, adapted to hold the cleats in position, and recessed to correspond with 80 the nail-punches, in order to permit the passage of nails to be driven through the cleats, substantially as described.

7. In a cleat-nailing machine, in combination, a nail-driving cross-head and connecting-links, nail-punches arranged to act in pairs, and a box-support with a rotary platen thereon, and means for bringing the cleats into alignment with the nail-punches, substantially as described. 85

8. In a cleat-nailing machine, in combination, a nail-driving cross-head, connecting-links arranged in pairs, simultaneously actuating at diverging angles, corresponding nail-punches, nail-boxes, a box-support, and means 95 for adjusting and retaining the cleats in position when being nailed, substantially as described.

9. In a cleat-nailing machine, in combination, nail feeding and driving mechanism, 100 means for retaining cleats in position when being nailed, a box-supporting table having pivoted thereon a rotary platen, carrying a registering-pad for centering the box when placed thereon, substantially as described. 105

10. In a cleat-nailing machine, in combination, nail feeding and driving mechanism, means for retaining cleats in position when being nailed, a box-supporting table having pivoted thereon a rotary platen, carrying a 110 registering-pad for centering the box when placed thereon, and stops for limiting the rotary movement of the platen, substantially as described.

Signed at New York city, in the county of 115 New York and State of New York, this 15th day of June, A. D. 1896.

WILLIAM S. DOIG.

WILSON W. HOOVER,
GEO. W. PAYNTAR.

Correction in Letters Patent No. 600,685.

It is hereby certified that in Letters Patent No. 600,685, granted March 15, 1898, upon the application of William S. Doig, of Brooklyn, New York, for an improvement in "Cleat-Nailing Machines," an error appears in the printed specification requiring correction, as follows: In line 55, page 3, the article "a" should be stricken out; and that the said Letters Patent should be read with this correction therein that the same may conform to the record of the case in the Patent Office.

Signed, countersigned, and sealed this 7th day of June, A. D., 1898.

[SEAL.]

WEBSTER DAVIS,
Assistant Secretary of the Interior.

Countersigned:

C. H. DUELL,
Commissioner of Patents.
